UNITED STATES PATENT OFFICE.

CHARLES H. KRAUSS, OF BIRMINGHAM, ALABAMA, ASSIGNOR TO MORRISON FROGLESS SWITCH COMPANY, OF BIRMINGHAM, ALABAMA, A CORPORATION OF ALABAMA.

FROGLESS SWITCH FOR RAILWAYS.

1,132,779.

Specification of Letters Patent. Patented Mar. 23, 1915.

Application filed September 8, 1914. Serial No. 860,820.

To all whom it may concern:

Be it known that I, CHARLES H. KRAUSS, a citizen of the United States of America, residing at Birmingham, in the county of 5 Jefferson and State of Alabama, have invented certain new and useful Improvements in Frogless Switches for Railways, of which the following is a specification.

My invention relates to an improvement 10 in frogless switches for railways and has for its object to improve and perfect the track structure and movable rail sections which take the place of the frogs in present switch structures.

15 One object of my present invention is to improve the fixed track structure by perfecting the manner of attachment to it of the converging rails, and by simplifying, lightening and cheapening its construction 20 without sacrificing the strength requisite for the duty on it.

A further object of my invention is to 25 provide the movable rail or frog point, which co-acts with the fixed track structure, with a roller bearing which works against the track structure and serves to take the track expansion thrust and keep the movable frog point from being jammed into the 30 pocket of the fixed track structure which receives it.

A further object of my invention is to 35 improve the manner of attaching the throw rod to the movable frog point, this connection in my construction making it possible for me to dispense with the use of "hold-downs" or like means to prevent the movable frog point leaving the bearing plates or track structure over which it slides.

40 A further object of my invention is to provide a safety lock acting on the throw rod and serving to lock the movable frog point in line with either track desired to prevent accidental displacement.

A further object of my present invention 45 is to simplify and reduce the cost of forming the movable frog point from rails and to provide a novel and exceedingly strong means for connecting such frog point to the converging ends of intermediate switch 50 rails.

My invention further comprises the details of construction and arrangement of parts which are hereinafter more particularly described and claimed, reference being had to the accompanying drawings,

which illustrate only the preferred embodiment of my invention, and in which:—

Figure 1 is a plan view of the fixed track structure, the movable frog point, and the operating mechanism for the latter. Figs. 60 2, 3, 4, 5 and 6, are enlarged cross sections taken on the lines A—A, B—B, C—C, D—D, and E—E, of Fig. 1. Fig. 7 is a sectional view on the line F—F of Fig. 4. Fig. 8 is a cross sectional view of the frog point connections to a track rail taken on the line 65 G—G of Fig. 9. Fig. 9 is a vertical sectional view taken on the line H—H of Fig. 8. Fig. 10 is a sectional view taken on the line J—J of Fig. 2 and showing the shape of 70 the shoulders provided to fit against the rail web and the splice bar.

Similar reference numerals refer to similar parts throughout the drawings.

As my present invention relates to the 75 structural details of the movable frog point and the fixed track structure with which it co-operates, I have dispensed with the illustration of the switch points, the outside track rails, and all but that part of the switch operating mechanism which shifts the frog point, as all of such parts not illustrated may be of any standard construction and form no part of my present invention. The movable frog point in its preferred embodiment is 80 formed by two angularly disposed rail sections 1 and 2 and an interposed wedge shaped filler block 3. The frog point, at its forward end, tapers to an acute angle so that, when in either of its operating positions, it 85 will make a smooth lap joint with one or the other of tread walls 4 of the fixed track structure 5. This structure is provided at its end adjacent to the frog point with an outwardly flaring pocket 6 which is formed by the tread walls 4 and the flat base of the structure on which the free end of the frog point rests and slides thereover to engage either tread wall 4. The rails forming the 90 frog point and their interposed filler block 95 are rigidly connected by a series of transverse bolts 7 which pass through them and through fish plates 8, as seen in Fig. 6. The filler block 3 is shaped to fit between the rails 1 and 2, while the wide rear end of 100 the block is tapered to present a gradually rising surface 9 which serves as an easer block for worn wheel treads. The frog point is connected to converging switch rails 1^a and 2^a which align respectively with the 105

frog rails 1 and 2. In order to secure an extremely strong connection between the meeting ends of the frog point rails and the rails 1^a and 2^a, and yet to allow the frog point to shift freely to its different operating positions, I provide at each joint two fish plates 10 which have suitable bolt openings therein. In the webs of the rail ends 1 and 2 I provide horizontally elongated slots 11. Bolts 12 connect the fish plates and pass through the web of the rails 1^a and 2^a and through the end slots 11 in the frog rails 1 and 2. In the inner slot 11 of each frog rail however I insert a sleeve 13, the ends of which project beyond the web of the frog rail and, being of larger diameter than bolt holes in the fish plates, they will positively engage and hold apart the inner ends of each pair of fish plates sufficiently to permit the free angular play between them of the frog point. A bolt 14 is passed through each pair of the fish plates and the interposed spreader sleeve of each rail joint and a tapered washer 15 is slipped over the threaded end of each bolt so as to provide a flat surface against which a nut can be screwed home to joint the fish plates tightly against the sleeve but without however rigidly clamping the web of either frog rail end between them. In other words, the fish plates are rigidly bolted together and yet leave the ends of the frog rail free to shift and move angularly between them so as to permit the V-shaped frog point to assume its different operating positions.

I attach slide plates 16 on the cross ties 17 to support the movable frog point, the pointed end of which works in the pocket 6 of the fixed structure 5. The pointed end of the frog point is formed by tapering and fitting together the ends of the rails 1 and 2, the side edges of the tread and base of the frog point rails, as indicated in Fig. 5, being squared off in the tapering so they will fit squarely against the squared inner side edges of the treads 4 of the track structure, which treads are formed by overhanging flanges integral with the structure 5. In order to prevent the switch point being jammed into the pocket by the expansion of the track rails I bolt to the under side of the movable frog a plate 17 (see Figs. 4 and 7) which is provided in its edge adjacent to the track structure 5 with a curved recess 18 struck on an arc having a radius which extends beyond the forward end of the plate. A circular opening is provided at the center of this recess which receives the stud 19 of an antifriction roller 20, the outer periphery of which roller projects beyond the front edge of plate 17 and is adapted to engage and bear against the rear end wall 21 of the track structure 5. In this manner the roller 20 will serve as an anti-friction bearing between the frog point and

the track structure which will receive any end thrust and prevent the jamming of the frog point in the pocket of the track structure.

The base of the pocket 6, beneath the end 70 of the frog point, is provided with a transverse slot 22 and I bolt to the sides of the web of the frog point, the base flanges of which have been sheared away as shown in Fig. 5, a pair of oppositely facing angle 75 bars 23, which bars extend below the frog point and through slot 22 and engage the wide base of the structure 5. These plates are riveted to a throw rod 24 and extend far enough on each side to remain always 80 in contact with the base of the structure 5 in all operating positions of the frog point. The throw rod 24 is pivotally connected by a link 25 with a bell crank lever 26 which is pivoted between ears 27 mounted on the 85 end of an angle plate 28 that is bolted to the end of a cross tie. A rod 29 connects the bell crank lever 26 to a similar lever 30 which in turn is connected by a rod 31 and link 32 to the throw mechanism for the 90 switch points (not shown). Metal straps 33 serve as guides for the rod 29 and support it below the top level of the cross ties to afford it better protection.

The angle bars 23 and throw rod 24 have 95 registering openings 34 therein adapted to receive a lock pin 35, the holes being so positioned that the pin, when inserted in one or the other of them and in engagement with a side edge of the base of the track 100 structure, will hold the frog point locked against the adjacent tread 4. The track structure itself is specially designed for lightness and strength and is therefore preferably made as a hollow casting of manganese steel or like hard and durable metal. As shown in Fig. 5 the treads 4, with which the frog point makes a lap joint, are formed by overhanging flanges which at their outer ends 36 are beveled downwardly to avoid 105 the possibility of their engaging any loose parts hanging under the trains, thereby causing the displacement of or damage to the track structure. Also the end of the frog point is beveled or slightly depressed below the tread level of the treads 4 to prevent the wheels hammering it. The structure has a vertical curved web 37 forming the inner end wall of the pocket 6 and terminating in the web 38 shown at the bottom 110 of the flange groove or throat 39, Fig. 3. The end of the track structure that connects with the track rails 1^b and 2^b which form a continuation of the rails 1^a and 2^a, respectively, is especially designed for furnishing 115 a strong and effective joint. To this end, as shown in Fig. 2, the tread faces 4^a are shown diverging and each is provided with an integral shoulder 40 which extends along its inner side from the adjacent end wall 37^a 120 to the 125 flange groove 39. The shoulder 40 is provided with a curved 130

of the throat to the outer end of the tread and conforms in cross section to the side of a rail. Above the shoulders 40 at the outer end of the treads 4^a, a notch-out is provided 5 to receive the tread of the rail 1^b or 2^b which make a lap joint with the alining tread 4^a. These notch-outs leave an offset portion extending between them and the wall 37 and form a continuation of the rail treads from 10 either rail 1^b or 2^b to the frog point. The inner shoulders of the notch-outs are squared and the rails 1^b and 2^b abut against them so that there is no possibility of displacement of the rails on the track structure 15 due to the expansion of the former. The offset portions of the treads 4^a are much wider than the treads 4. The shoulders 40 are cast with sockets 41 in line with side openings for bolts 42 which are passed 20 through the shoulder and abutting rail web and through an inner fish plate 43, tying all parts rigidly to the track structure. The inner face of the shoulders 40 are reduced the thickness of the rail web where they are 25 overlapped by the web so that the wall of the latter that engages the fish plate will stand flush with the inner face of the shoulder which also engages the fish plate. This affords an exceedingly strong and effective 30 joint in which the rail and track structure are tied against strain in every direction, it being noted that the fish plates extend beyond the rail ends to the wall 38 and that a large number of bolts are used to connect 35 them to the track structure. The outer ends of the treads 4^a are beveled at 36 as in the case of the treads 4 and the inner ends of the rails 1^b and 2^b are also slightly beveled. The track structure is provided with a base 40 flange by means of which it is spiked to the cross ties.

The angle bars 23 and the throw rod 24 being connected to the switch point above the track structure, and being in slidable 45 engagement with the wide base of the track structure, serve to effectively hold the frog point against vertical displacement with reference to the track structure and to slide plates 15 and therefore enables me to dispense with "hold-downs" or like attachments which have heretofore been required for movable frog points and at the same time I avoid any necessity for longitudinally slotting the track structure at the side 50 to connect the throw rod to the frog point. This arrangement leaves the throw rod free to swing in following the arcuate travel of the frog point.

In operation, as the track switches are 55 thrown to the main or the siding, the operating connections shown will swing the frog point so as to bring it into alinement with one or the other of the treads 4^a as to establish a continuous rail line for the 60 wheels where they cross the projected in-

tersection of tracks 2^a, 2^b, and 1^a, 1^b. The connection shown for the rear ends of the frog point leaves it free to swing without there being any flexing of the metal or risk of breakage at the joints with the rails 1^a 70 and 2^a and the antifriction rollers 20 avoids the possibility of the frog point being jammed and locked in the socket of the track structure. The offset tread portions of the treads 4^a which are interposed between the rails 1^b and 2^b and the frog point, give a continuous rail and the connections of the said rails and the frog point to the track structure are such as to prevent any 75 possibility of the mechanism not presenting 80 to the wheels an even continuous tread with the inner edges of its sections in alinement.

Having thus described my invention, what I claim as new and desire to secure by Letters Patent, is:—

1. In a frogless switch, the combination of a frog point having divergent rail treads, means to connect said treads to track rails, a track structure with which said movable frog point co-acts and which has divergent 90 treads connected to track rails, and an anti-friction bearing interposed between the frog point and the track structure, as and for the purposes described.

2. The combination with a track structure 95 having divergent rail treads, of a movable frog point having its free end supported on said structure, tread surfaces on said structure with which said frog point is adapted to make a lap joint, a roller bearing connected to the underside of the movable frog point, and a transverse bearing face on the track structure which said roller bearing engages, substantially as described.

3. In a frogless switch mechanism, a track 105 structure having at each side divergent treads, track rails connected to said treads at one end, a movable frog point adapted to make a lap joint with one or the other of the treads at the other end of the structure, 110 said treads at the latter end of the structure forming a pocket which receives the frog point, a bearing connected to the underside of the frog point, a roller mounted in said bearing, and a transverse vertical end wall 115 of the track structure which is adapted to form a track for the roller and prevent the frog point jamming in said pocket, substantially as described.

4. A track structure comprising an integral casting having divergent treads which are continuous from end to end of the casting, a base connecting the divergent treads at one end and forming with them a pocket, a tapering frog point having its free end 125 supported on said base and adapted to make a lap joint with one or the other of the side treads of said pocket, a transverse slot in the base of said pocket, operating connections for the point comprising a throw rod, 130

brackets mounted on the throw rod and adapted to slidingly engage the base of the track structure and arms of the brackets which project upwardly through said slot 5 on each side of the frog point, and cross bolts to rigidly attach said bracket arms to the frog point, substantially as described.

5. In a track structure having divergent tread members at one end, a pocket for receiving a movable frog point, said pocket having side treads, which form continuations of said divergent treads, and a transversely slotted base, one or more brackets having vertical arms connected to the side 10 of the frog point and extending down through the slot in said base, and a throw rod connected to the horizontal members of said bracket or brackets which are held in sliding engagement with the under wall of 15 the track structure to take the friction wear and hold down the frog point in sliding engagement with the pocket base, substantially as described.

6. A track structure for a frogless switch 25 mechanism comprising an integral casting having along each side a tread, which treads converge from each end of the structure toward a center or throat portion thereof, the treads at one end having between them a 30 base and being adapted to receive and form a lap-joint with a movable switch point, and the treads at the other ends of the structure having inside shoulders for interfitting with the side groove of a rail, the throat or 35 central portion of the structure having walls facing toward each end of the structure and connected at their tops by a horizontal integral wall raised above the level of the base which receives the frog point, substantially 40 as described.

7. A track structure for frogless switch mechanism comprising an integral casting having at one end relatively narrow divergent tread walls 4 and at the other end the 45 wider tread walls 4^a, both walls converging toward the center or throat of the structure, the latter walls being notched out along their inner side edges at the outer ends of 50 their treads and having inwardly disposed shoulders along their inner side walls which conform in side contour to the shape of a side of a track rail and extend below and beyond said notches to points adjacent to the throat of the structure, track rails which 55 fit against and over said shoulders with their tread ends abutting the inner ends of said notches, inside splice bars which lap the joint between the track rails and said shoulders on the treads 4^a, and means to bolt said splice bars and rails to the track 60 structure, substantially as described.

8. A track structure for a frogless switch mechanism comprising a hollow casting formed with a base flange and having at 65 one end divergent treads 4^a with notch-outs

to receive the treads of track rails and form a butt-joint therewith, a pocket formed at the other end of the track structure and comprising a base, and narrow marginal tread walls 4 formed by overhanging flanges 70 of the track structure, said structure having an intermediate raised throat 38 connecting the treads 4^a, the base of the throat being raised above the base of the pocket and being connected to the base of the 75 pocket by a vertical web, substantially as described.

9. In a frogless switch, two converging track rails, a movable frog point with which said rails connect, other converging track 80 rails, a frog structure with which said latter rails connect and which comprises a pair of tread walls which converge from each end toward the center or throat of the structure, the tread walls at one end being adapted to receive between them the frog point and the tread walls at the other end being wider than the track rail treads and provided with notch outs extending inward a substantial distance from the end of the 85 tread wall and adapted to receive the rail treads which abut against the inner end wall of the notch out, and means to move said point to make a lap joint with one or the other of the adjacent tread walls, said 90 notch outs leaving an offset portion of each wall which projects between the frog point and the alining track rail attached to said structure to form a continuous tread for the wheel in passing from rail to rail over the 95 frog point in either direction.

10. In a track structure for a frogless switch, an integral casting having along its sides tread walls which converge from the ends toward a contracted throat at the center, the treads at one end having a greater width than the track rail treads and being notched out along their inner edges corresponding to the width of the track rail treads, reinforcing shoulders which extend 105 along the inner walls of said side walls from the ends where the treads are notched to points adjacent to the throat of the structure, which shoulders below the notches are reduced the thickness of the rail web, said 110 shoulders conforming to the side of the rail, a fish plate which laps the joint between the rail web and said shoulder, and bolts which pass through the shoulder and attach both ends of the fish plate to said structure, substantially as described.

11. In a track structure, a pocket at one end adapted to receive a movable frog point, and integral divergent walls at the other end which walls form treads wider than the 115 rail treads, said wall treads being notched out at the inner side of their outer ends to make a lap and butt joint with rail end and a shoulder, on a wall of said structure, which projects laterally sufficiently to en- 120

gage the web of a track rail and extends lengthwise in both directions from the inner end of the notches, a fish plate which laps the joint between the track rail and shoulder and bolts which pass through said shoulder for attaching the fish plate and rail to the structure.

12. In a track structure, an integral casting having at one end a pocket for a movable frog point, and having marginal side walls the tops of which are inturned to form overhanging treads, an intermediate transverse web connecting the treads near their center,

and disposed substantially below the surfaces of the treads, and shoulders, below the treads adapted to be jointed to fixed track rails, which shoulders conform to the side of the fixed track rails and are offset laterally at an intermediate point to make a butt joint with the webs of the said fixed rails. 20

In testimony whereof I affix my signature in presence of two witnesses.

CHARLES H. KRAUSS.
